U.S. Cl. D22—10

FIG. 1

FIG. 3

FIG. 2

FIG. 5

FIG. 4

FIG. 1 is a side elevational view of a seismic gas exploder embodying my design. The three fastening means on the canvas cover are partially shown in dotted lines which indicate stitching.

FIG. 2 is a side elevational view of the seismic gas exploder with the canvas cover removed.

FIG. 3 is a top plan view thereof.

FIG. 4 is a bottom plan view thereof.

FIG. 5 is another side elevational view thereof.

The third side elevational view is similar to the one shown in FIG. 5.

The broken lines are shown for illustrative purposes only. The canvas cover is omitted from FIGS. 2, 4, and 5 for purposes of disclosure.

I claim:

The ornamental design for a seismic gas exploder, substantially as shown and described.
